UNITED STATES PATENT OFFICE.

OTTO H. L. WERNICKE, OF GULL POINT, FLORIDA.

ART OF DESTRUCTIVE DISTILLATION.

Application filed September 9, 1921. Serial No. 499,495.

The present invention relates to the art of destructive distillation of matter and more particularly resinous or pitchy woods such as "fat" pine wood and the like. It will be 5 fully understood from the following description, illustrated by the accompanying drawing, which shows in broken elevation, and partly in section, apparatus suitable for carrying the invention into effect.

10 Referring more particularly to the drawing, the numeral 5 indicates the end of a suitable retort which is connected by means of a vapor conduit 6 with a vertical tubular condenser 7. The cooling medium, usually 15 water, is admitted to the condenser-tubes through the pipe 8 and passes out through the pipe 9. The cooled gases and condensed liquids issue from the lower end of the condenser through a discharge outlet 10, which 20 communicates with a trapped outlet 11 for the liquid products of distillation. The trap in outlet 11 prevents the discharge of gas therethrough. Uncondensed gas is discharged through the vertical outlet 12 which 25 is closable by means of the valve 13. The gases which are discharged past the valve enter the chamber 14 provided with an outlet 15 from which they may be disposed, or allowed to escape. Baffles 16 may be provided 30 in the upper portion of chamber 14 to hold back entrained liquid carried by the gas.

35 The valve 13 is balanced so that it opens automatically when the pressure in the condenser and still rises above that beyond the gas discharge, and closes when the pressure in the condenser and still equals or falls below that beyond the gas discharge. A suitable construction for accomplishing this 40 purpose is shown in the drawing. The valve is provided with an upright stem 17 which is guided in a spider 18. A weighted lever 19, pivoted outside the expansion chamber 14, engages the valve stem 17 and is so adjusted as to cause the valve to open when 45 the pressure below it exceeds that beyond the gas discharge and close, upon the formation of an appreciable vacuum in the condenser and still or at a pressure therein equal to 50 that beyond the gas discharge.

55 In destructively distilling matter, and particularly fatty or resinous woods, the distribution of heat within the retort is in general very irregular, some portions of the retort being highly heated while other portions thereof are at relatively low tempera-

ture. The distillation vapors formed at low temperatures, of which there are large proportions in such fatty or resinous woods, are very sensitive to excessive temperatures, 50 decomposing with the formation of incondensable gas and the destruction of valuable products. In order to avoid the application of such high temperatures to these products of distillation, it is desirable that 55 they be withdrawn from the retort as rapidly as possible. The entire range of products are ordinarily passed through a condenser, which by its condensing action is often sufficient to create a slight and desirable vacuum in the retort. Under other circumstances fixed gases are formed causing a 60 back pressure in the condenser and retort, and the products of distillation are thus restrained in the retort and are further decomposed with the formation of more fixed gas. 65

In accordance with the present invention, when a proportion of fixed gas becomes such as to cause pressure in the retort and condenser exceeding the pressure beyond the 70 valve outlet, the valve plate 13 is unsealed until equilibrium is re-established. The gas outlet 13, however, automatically closes when the pressure in the condenser and the retort becomes equal to or less than that beyond 75 the gas discharge, thereby preventing suction of air into the condenser during the periods of operation in which its action produces a vacuum in the retort. The suction of the condenser is thereby exerted solely 80 upon the retort and the sensitive vapors of the distillation products are rapidly withdrawn, substantially unaffected by the irregular heating or overheating of the retort. 85

Although the present invention has been 90 described in connection with the specific details of an embodiment thereof, it is not intended that these details shall be regarded as limitations upon the scope of the invention, except in so far as included in the accompanying claims. 95

I claim:

1. The improvement in the method of destructively distilling woody materials where-in the products of distillation are subjected 105 to partial condensation, which comprises freely discharging all liquids and gases from the condenser under substantially atmospheric pressure conditions during the entire run while automatically counteracting suction into the condenser from beyond the gas discharge. 110

2. The improvement in the method of de-
structively distilling woody material where-
in the products of distillation are subjected
to partial condensation, which comprises
5 trapping out the liquid from the gaseous
products of condensation, freely discharging
the gaseous products under substantially ex-
ternal atmospheric conditions, and automatic-
ally counteracting back suction during such
10 periods in which the pressure in the con-
denser is not above that beyond the gas dis-
charge.
3. In wood distillation apparatus, a retort
or still, a condenser into which the vapors
15 from said retort or still are discharged, an
outlet from said condenser through which
the liquid and gaseous cooled products are
passed, a trapped liquid discharge communi-
cating with said outlet, a gas discharge
20 communicating with said outlet, a baffled
expansion chamber into which said gas dis-
charge opens, a self acting valve seated upon
said gas discharge in said expansion cham-

ber, and balancing means engaging the valve,
adjustable to open the valve when the pres-
sure in the retort and the condenser exceeds
that beyond the gas discharge and to close
it when such pressure does not exceed that
beyond the gas discharge. 25

4. In wood distillation apparatus, a retort 30
or still, a condenser into which the vapors
from said retort are discharged, an outlet
from said condenser through which the liq-
uid and gaseous cooled products are passed,
a trapped liquid discharge communicating 35
with said outlet, a gas discharge communi-
cating with said outlet, an expansion cham-
ber into which said gas discharge opens, a
self-acting valve seated upon said gas dis-
charge in said expansion chamber, said valve 40
opening when the pressure in the retort and
the condenser exceeds that beyond the gas
discharge and closing when such pressure
does not exceed that beyond the gas dis-
charge. 45
